US00D977430S

(12) **United States Design Patent** (10) Patent No.: **US D977,430 S**
(45) Date of Patent: **** Feb. 7, 2023**

(54) **SOCKET**

(71) Applicant: **Xiaoqin Zhou**, Jurong (CN)

(72) Inventor: **Xiaoqin Zhou**, Jurong (CN)

(**) Term: **15 Years**

(21) Appl. No.: **29/799,736**

(22) Filed: **Jul. 16, 2021**

Related U.S. Application Data

(63) Continuation-in-part of application No. 29/798,250, filed on Jul. 7, 2021, now Pat. No. Des. 961,521.

(57) **CLAIM**

The ornamental design for a socket, as shown and described.

DESCRIPTION

FIG. 1 is a perspective view of a first Group of a socket showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2;

FIG. 10 is a perspective view of a second Group of the socket;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is an enlarged view of portion 18 shown in FIG. 1.

The dash-dash broken lines in the drawings depict portions of the socket that form no part of the claimed design. The dot-dash broken lines represent boundaries of the enlarged portions and form no part of the claimed design.

1 Claim, 18 Drawing Sheets
